Primary Examiner—Ruth McInroy*Attorney, Agent, or Firm*—A. Burgess Lowe[57] **CLAIM**

The ornamental design for an upright extractor base module, as shown and described.

DESCRIPTION

FIG. 1 is a left side elevational view of an upright extractor base module showing my new design;

FIG. 2 is an enlarged left side elevational view thereof;

FIG. 3 is an enlarged front elevational view thereof;

FIG. 4 is an enlarged rear elevational view thereof; and,

FIG. 5 is an enlarged top plan view thereof.

The right side elevational view of my upright extractor base module as claimed herein is a reversed image of FIG. 2.

The details shown in broken lines are shown for illustrative purposes only and form no part of the claimed design.
